UNITED STATES PATENT OFFICE.

MORRIS BASSION, OF PHILADELPHIA, PENNSYLVANIA, ASSIGNOR TO JOSEPH RENDELMAN AND MORRIS BASSION, COPARTNERS TRADING AS ACME AUTO TOP AND PAINTING COMPANY, OF PHILADELPHIA, PENNSYLVANIA.

UMBRELLA AND HAT RACK.

Application filed May 31, 1927. Serial No. 195,179.

My invention relates to umbrella and hat racks and has for its objects to provide a rack having a large capacity relative to its size, of pleasing appearance and having novel and efficient means for disposing of the water which may be deposited therein from wet umbrellas or garments. Other objects are to provide an umbrella and hat rack which is of sturdy and simple construction and in which the hat rack may be telescoped into the umbrella rack when not in use.

These objects, and other advantageous ends which will appear hereinafter, I attain in the following manner, reference being had to the accompanying drawings in which

Figure 1 is a top plan view of an umbrella and hat rack embodying my invention, and

Figure 2 a vertical cross-sectional view of same, taken substantially on line 2-2 on Figure 1.

Figure 3 is a perspective view of an embodiment of my invention, showing same in use,

Figure 4 a bottom plan view of the base of the rack shown in Figure 3, and

Figure 5 a fragmentary vertical cross-sectional view of the device shown in Figure 3, drawn to an enlarged scale.

Referring now more in detail to the drawings, the device is provided with a base 10 which is preferably cast in some ornamental design and which has a cup-like extension 11 extending upwardly and preferably cast integral therewith. A perforated diaphragm 12 is disposed on top of extension 11 and supports a body part 13 which is preferably composed of sheet metal and shaped to resemble an umbrella in partially opened position. A plurality of braces 14 have one end of each secured to a folded-in portion of body part 13, extend inwardly and upwardly and have their inner ends securely joined to a central tube 15 by being welded or otherwise secured to a clamp 16 fixed to the tube and designed to represent the sliding ferrule found at this point in umbrellas. The lower end of tube 15 extends through base 10 and has a nut 17 threaded thereon in such a manner that tube 15 holds body part 13, diaphragm 12 and base 10 in fixed relation to one another.

The portion of tube 15 disposed within extension 11 is provided with a plurality of small openings 18 adapted to drain water from extension 11 into a receptacle 19 remov-

ably secured to the underside of base 10. Receptacle 19 may be secured to base 10 in any suitable manner but I have illustrated it as being supported on two fixed lugs 20 and a spring lug 21, as shown in Figure 4. Spring lug 21 has been shown as having a spring portion 22 which terminates in a flange 23 secured to base 10; the two lugs 20 and spring lug 21 being so spaced from one another that they will support receptacle 19 but will allow spring lug 21 to be moved outwardly enough to permit the removal of receptacle 19.

A rod 24 is slidably mounted in the upper end of tube 15 and adapted to be held in selected positions by the set screw in clamp 16; it being understood that one or more spring latches, of the same type as are used to hold umbrellas in open position, may be mounted in rod 24 and replace the set screw. The upper end of rod 24 is provided with a plurality of hooks 25, for supporting hats and wraps, and an ornament 26, which preferably represents the handle of an umbrella, is secured to the upper end of rod 24 in order to give the stand a finished appearance.

In order to further give the device the appearance of an umbrella, I provide a series of small projections 27, extending from the upper edge of the body part at the points which would be normally occupied by ribs in an ordinary umbrella, and these projections may be utilized for suspending overshoes, or other small articles, on the edge of the body part.

Umbrellas placed in body part 13 are supported by diaphragm 12 and any water which may drain from the umbrellas passes through the perforations in the diaphragm, into extension 11, through openings 18 and tube 15, into receptacle 19. Wet hats or garments may be hung upon hooks 25 and the water dripping therefrom will be caught by body part 13 and directed into receptacle 19, as above described. By pressing the end of spring portion 22, receptacle 19 may be released from its supporting lugs and emptied. When hooks 25 are not in use, rod 24 may be telescoped into tube 15 so that the device will present a more attractive appearance.

While I have described my invention as taking a particular form, it will be understood that modifications may be made without departing from the spirit thereof, and hence I do not limit myself to the precise

construction set forth, but consider that I am at liberty to make such changes and alterations as fairly come within the scope of the appended claims.

5. I claim:—

1. A device of the character described including a base; a cup-like extension on the base; a perforated diaphragm on top of the extension; an umbrella shaped body part resting on the diaphragm; braces fixed to the body part and extending upwardly to represent the ribs of an umbrella; a clamp fixed to the upper ends of the braces; a tubular member, having its upper end fixed to the clamps and its lower end secured to the base, holding all of said parts together; and means for draining water from the extension.

2. A device of the character described including a base; a cup-like extension on the base; a perforated diaphragm on top of the extension; an umbrella shaped body part resting on the diaphragm; braces fixed to the body part; a tubular member secured to the braces and extending through the base, the tubular member having perforations communicating with the extension; and a nut threaded on the tube for securing the body part to the base.

3. A device of the character described including a base; a funnel shaped extension on the base; a perforated diaphragm on top of the extension; an umbrella shaped body part resting on the diaphragm and having its sides in alignment with the sides of the extension; a tubular member, having perforations communicating with the extension, extending through the base and securing the body part to the base; a receptacle beneath the base; and means for supporting the receptacle.

4. A device of the character described including a base; a hollow frusto-conical extension having its small end formed integral with the base; a perforated diaphragm on top of the large end of the extension; an umbrella shaped body part resting on the diaphragm; a tubular member, having perforations communicating with the extension, extending through the base and securing the body part to the base; a receptacle beneath the base; fixed lugs on the base; a spring fixed on the base and extending parallel therewith; a lug on the spring; and a flange on the receptacle engaging all of said lugs.

In testimony whereof I have signed my name to this specification.

MORRIS BASSION.
